WITNESS:

UNITED STATES PATENT OFFICE.

ARTHUR FLOM, OF ATHELSTONE, WISCONSIN.

DISPENSING DEVICE.

Application filed March 13, 1922. Serial No. 543,251.

To all whom it may concern:

Be it known that I, ARTHUR FLOM, a citizen of the United States, residing at Athelstone, in the county of Marinette and State 5 of Wisconsin, have invented new and useful Improvements in Dispensing Devices, of which the following is a specification.

This invention relates to brushes, particularly those of the fountain type and has for 10 its object the provision of a novel tooth brush having a handle within which is stored the tooth paste or other cleansing material, the handle being provided with means for expelling the material through the brush, the 15 device having the great advantage of eliminating the necessity of squeezing out a certain quantity of paste or the like on to the face of a brush as is the usual practice.

An important object is the provision of a 20 fountain brush of this character which is so constructed that it may be quickly and easily filled with the contents of a commercial package of tooth paste or the like, the handle being hollow for this purpose and the expelling 25 means being removable.

A further object is the provision of a device of this character which will be economical as it will prevent the drying up of the material and which will be sanitary as protecting the material from contact with the 30 hands or with the air until it is pressed out onto the brush.

An additional object is the provision of a device of this character which will be simple 35 and inexpensive in manufacture, easy to operate, efficient and durable in service and a general improvement in the art.

With the above and other objects and advantages in view, the invention consists in 40 the details of construction to be hereinafter more fully described and claimed, and illustrated in the accompanying drawings, in which:

Figure 1 is a side elevation of the brush 45 complete,

Figure 2 is a longitudinal sectional view,

Figure 3 is a similar view showing the operation of filling the paste chamber,

Figure 4 is a cross section on the line 4—4 50 of Figure 2.

Referring more particularly to the drawings the numeral 10 designates a cylindrical hollow body which has one end open and formed with a threaded reduced flange 11 55 and which has its other end formed with a

reduced externally threaded extension 12 having a threaded hole 13 therein. The numeral 14 designates a back having one end externally threaded and engaged within the hole 13. Secured to the back in the usual 60 manner are the bristle tufts 16 which may have their working faces of any desired configuration. The back is formed with a longitudinal channel 17 which communicates with holes 18 leading into or among the 65 bristle tufts.

Screwed upon the flange 11 is a tubular member 19 which has both ends open and which has its inner wall threaded. Rotatably mounted upon one end of this member is an 70 operating cap or button 20 which is flanged to extend over the member 19 and which carries a pair of spaced guide rods 21 having their ends connected by a disk 22 through which is slid able a stem 23 having one end 75 provided with a plunger head 24 and having its other end carrying a cross head 25 extending between and beyond the guide rods 21 with its opposite edges notched as shown at 26 and engaging the threads within the 80 member 19. The plunger head 24 is of such size as to slide readily within the body 10.

In order to fill the body 10 with tooth paste it is necessary to unscrew the member 19 from engagement therewith after which 85 a tube of tooth paste may have its open end disposed within the flanged end of the body 10. By squeezing the tube A of tooth paste and rolling up its butt end in the usual manner the entire contents will be discharged 90 into the body 10. The member 19 is then screwed on to the flange 11 and it is to be

noted that before this is done the plunger 24 should be moved to its retracted position, that is: with the cross head 25 disposed immediately adjacent the operating cap or button 20. When it is desired to use the brush, rotation of the cap or button will cause the guide rods 21 to rotate the cross head 25 plunger 23. Owing to the fact that the 100 cross head 25 is formed with the notches 26 engaging the threads on the interior of the member 19, the rotary movement will cause the plunger 24 to be advanced into the body 10 and to exert pressure upon the mass of 105 tooth paste therein. This will result in forcing the tooth paste through the channel 17 and out through the holes 18 among the bristle tufts. The brush may then be used 110 in the ordinary manner. After all the paste

has been consumed the member 19 is removed and the same operation of refilling is gone through with.

I prefer to employ a cap 27 for the purpose of enclosing the brush head when the device is not in use and this cap has one end internally threaded and screwed upon the externally threaded extension 12 of the body. The other end of the cap is closed and may 10 be provided with a ring 28 by means of which the device may be suspended from a nail or hook in the lavatory, and it may be advantageous to provide a clip 29 on the cap by means of which the device may be retained within the pocket in case it is desired to carry it around.

From the foregoing description and a study of the drawings it will be apparent that I have thus provided a simply constructed and consequently inexpensive form 20 to contain tooth brush within which the paste is contained at all times ready for use and kept in a sanitary manner. It is manifest that the device will be a distinct convenience and will avoid the annoyance of handling the well known collapsible paste tubes which so frequently become clogged or bursted. Owing to the simplicity of the construction and the fewness of the parts it is 25 apparent that there is nothing to get out of order and that the device should consequently have a long life and satisfactorily perform all the functions for which it is intended.

30 While I have shown and described the preferred embodiment of the invention, it is of course to be understood that I reserve the right to make such changes in the form, con-

struction and arrangement of parts as will not depart from the spirit of the invention 40 or the scope of the subjoined claims.

Having thus described my invention I claim:

1. In a device of the character described, a hollow body adapted to contain a semi-45 liquid material, a discharge nozzle at one end of the body, a transverse support within the body, a plunger located within the body between said support and the nozzle, a stem on which said plunger is supported, a plurality of guides carried by said support, a cross head on the stem slidable along said guides, one end portion of the body being internally threaded and the ends of the cross head being engaged with the threads, 55 and a cap rotatable upon the end of the body most remote from the nozzle and secured to said guides.

2. In a dispensing device, an elongated tubular body provided at one end with a nozzle and adapted to contain semi-liquid material, a tubular shell detachably connected with said body and internally threaded, a transverse partition within the shell at its juncture with the body, guide rods secured in said partition, a plunger operating within the body and carried by a stem slidable through the partition, a cross head on the stem slidable along said guide rods, and having threaded ends engaging the interior 65 of the shell, and a cap rotatably mounted on the outer end of the shell and secured to said guide rods.

In testimony whereof I affix my signature.

ARTHUR FLOM.
